(57) **CLAIM**

The ornamental design for a cable clamp as shown and described.

DESCRIPTION

FIG. 1 is a perspective view of a first embodiment of a cable clamp according to the present invention;

FIG. 2 is a first side view of FIG. 1;

FIG. 3 is a second side view of FIG. 1;

FIG. 4 is a first end view of FIG. 1;

FIG. 5 is a second end view of FIG. 1;

FIG. 6 is a top view of FIG. 1;

FIG. 7 is a bottom view of FIG. 1;

FIG. 8 is an additional perspective view of FIG. 1;

FIG. 9 is a perspective view of the first embodiment also illustrating fiber optic cables and a strap for environmental context; and,

FIG. 10 is an additional perspective view of the first embodiment also illustrating fiber optic cables and a strap for environmental context.

The portions of the cable clamp shown in broken lines form no part of the claimed design. The broken line showing of portions of fiber optic cables and straps in FIGS. 9-10 depicts environmental subject matter and forms no part of the claimed design.

1 Claim, 8 Drawing Sheets
